UNITED STATES PATENT OFFICE.

JOHN A. SHISHUK, OF MINNEAPOLIS, MINNESOTA.

GRAIN-CAR DOOR.

Application filed January 26, 1924. Serial No. 638,705.

My invention relates to improvements in grain car doors.

The closure commonly employed for grain car doorways consists of a number of door sections, which are placed edge on edge across a doorway and nailed at their ends to the inner sides of the door post or to nailing strips on said posts. In unloading a car thus equipped, the lowermost door section is dislodged to permit the grain to flow from the car. Expensive and cumbersome devices have been constructed with the view of removing such lowermost door sections from grain sealing position, but these devices like the hand tools ordinarily employed invariably result in damage or destruction to said door sections during the dislodgement thereof from a loaded car. Though relatively inexpensive, the waste occasioned in the breakage of these simple door sections is very great. Numerous closures have been devised as substitutes for all or certain of the usual grain door sections, but they have not met with such favor as to supplant the use of the ordinary sections.

An object of my invention is to provide a car door including the ordinary or similar door sections and a simple, durable, and inexpensive door holding means readily applicable to a car door frame, said means being adapted to normally secure one end of the lowermost door section against outward dislodgement from grain sealing position and capable of operation to allow for the quick and easy removal of said door section without injury thereto.

With the foregoing and other objects in view, which will appear in the following description, the invention resides in the novel combination and arrangement of parts and in the details of construction hereinafter described and claimed.

In the drawings, Fig. 1 is an elevational view illustrating superimposed door sections extending across a car door opening and showing holding means engaged with the lowermost door section; Fig. 2 is a vertical sectional view taken on the line 2—2 of Fig. 1; Fig. 3 is a similar view taken on the line 3—3 of Fig. 1; Fig. 4 is a horizontal sectional view taken on the line 4—4 of Fig. 2; Fig. 5 is a similar view taken on the line 5—5 of Fig. 2; Fig. 6 is a fragmentary perspective view illustrating a portion of my

improved door in connection with a part 55 of an ordinary car door frame; Fig. 7 is a fragmentary perspective view showing an alternate arrangement of the parts illustrated in Fig. 6 and Fig. 8 is a sectional view similar to Fig. 2, the same showing an alternate form of door holding means, the lowermost door section being illustrated in dotted lines.

Referring to the drawings, it will be observed that my door structure includes a 65 number of the usual door sections *a* and a door holding device *B*, the latter comprising an encasing body *b*, an abutment 10 slidable in the body and anchoring bolts 11 extending through said body, slidable abutment 10 and 70 car door frame.

The body *b* corresponds in width to an ordinary car door post 12 and its height is equal to the width of the widest door sections *a*. Said body preferably comprises a 75 steel forging or casting consisting of a side plate 13, base flange 14, top flange 15, and end flange 16, turned back from said side plate 13. I have illustrated this body *b* as applied to the customary freight car structure 80 including the usual door post 12, outer siding boards 17, inner lining 18 and nailing strip 19 (Figs. 2 and 3) fastened inside of said lining at the margin of the door frame. To apply the door holding device *B* to a door 85 frame in a car structure of this kind, it is only necessary to cut away the lower portion of the nailing strip 19 at one side of the doorway so that the base flange 14 of the body *b* may rest upon the car flooring 20 and 90 the top flange 15 fit snugly beneath the nailing strip 19. The anchoring bolts 11, fitted with nuts 11^a at their outer extremities, extend through the body *b* and door frame and hold said body rigidly in place, 95 against the inner lining 18. Said bolts reaching through horizontal guide slots 21 in the abutment 10 slidably support said abutment. The ends of the guide slots 21 are 100 turned upward to form notches 21^a, 21^b, said notches being designed to engage with the anchoring bolts 11 and retain the abutment 10 in inoperative and operative positions.

The face 19^a of the nailing strip 19 forms 105 the closure bearing surface of the door frame against which the door sections *a* are usually nailed. The inner or bearing surface of the abutment 10 lies in the plane of the face of

this nailing strip and the face of the companion strip at the opposite side of the door frame, said abutment being thus positioned by means of spacing washers 22 and a filler strip 23. Said filler strip 23 occupies the space within the body *b*, between the abutment 10 and the inner lining 18, while the spacing washers 22 are located on the anchoring bolts 11 between the plate 10 of the body *b* and said abutment. A recess 24 in the outer edge of the filler strip 23 serves to expose an indentation 25 in the abutment 10, when said abutment is sheathed within the body *b*.

15 To prepare the car for loading, the abutment 10 is shifted into position projecting into the doorway (Fig. 6), wherein it is latched by the engagement of the bolts 11 with the notches 21^b. One end of the lower door section *a* (Fig. 4), instead of lapping the nailing strip 19^a in the usual manner, is abutted against the body *b* with the outer margin of said end against the bearing surface of the abutment 10. The opposite end 20 of said door closure section overlaps the face of the nailing strip at the opposite side of the door frame and is tacked thereto. After the lower door section *a* is thus positioned, a second section is placed edgewise upon the 25 first and a third section upon the second and so on until the door is high enough to suit the immediate needs, those sections except the lowermost section being lapped at their ends over the nailing strips of the door frame 30 and tacked thereto. It will be observed that the top flange 15 of the body *b* extends beyond the face 19^a of the nailing strip 19 and forms a shelf. If the width of the lower door section *a* is equal to the height of the body *b*, the lower edge of a second door section *a* will 35 rest snugly upon the upper edge of said lower section and the top flange 15 of the body *b*. In loading the car, the pressure of the grain or other loose lading against the lower door section *a* holds the end of said section adjacent the door holding device B firmly against the abutment 10.

When the car is to be unloaded, the abutment 10 is raised sufficiently to disengage the 40 notches 21^b from the anchoring bolts 11 as by means of a crow bar or other suitable tool applied to the lower edge of said abutment. The abutment is then slid to its inner position within the body *b*, wherein it is latched 45 by engagement of the bolts 11 with the notches 21^a. As said abutment clears and frees the end of the lower door section *a*, the pressure of the grain from within the car swings said end outwardly. The dislodgment of the lower door section *a* permits the grain to flow from the car, the rate of flow being readily controlled by the 50 degree to which the door section is permitted to be swung outwardly. The top flange 15 and end flange 16 close the body 55

b against the entry of grain thereto from within the car. The end flange 16 forms an obtuse angle with respect to the side plate 13 and, in effect, provides a beveled end (Figs. 4 and 5) for the body *b*. This arrangement protects the body *b* against injury from or displacement by the various freight discharging devices in common use.

In some freight cars the inner lining and nailing strips are omitted as shown in Fig. 7. Under such conditions, the body *b*, constructed as hereinbefore described, is fitted into a recess cut in the door post 12'. With the door holding device B thus located, the inner face of the abutment 10 rests in the plane of the faces of the opposed door posts, said posts and the top flange 15 of the body *b* serving as bearing surfaces for the door sections in the manner above described. In instances where the width of the lower door section is less than the height of the body *b* a triangular crack is left between said lower door section and the second door section by reason of the latter resting at one end on the flange 15 of the body *b*. This crack or opening is readily closed to prevent the loss of grain therethrough by tacking a batten strip or a spare door section over said crack from within the door structure.

I employ an alternate form of door holding device B' (Fig. 8), in which the previously described filler strip 23 and washers 22 are omitted and wherein the top flange 15, end flange 16 and base flange 14 are reduced in width. In this form, the device may be recessed in the post 12 to bring the inner face of the abutment 10 precisely into the plane of the bearing surface of the post 12, but this is not necessary as will be observed from Fig. 8 of the drawing, wherein the inner face of the abutment 10 is shown as resting in a plane slightly inside of the plane of the face of the post 12. The distance between said planes amounts only to the thickness of the abutment 10 and this being one-fourth or less of the thickness of a door section *a* leaves ample grain sealing areas between the meeting edges of the lower and second door sections. Even if the upper edge of the lower door section does not meet the lower edge of the second section, the inner faces of said sections are so nearly co-planar that no difficulty is met in closing the space with a batten strip or one of the usual door sections.

Changes in the specific form of my invention, as herein disclosed, may be made within the scope of what is claimed without departing from the spirit of my invention.

Having described my invention, what I claim as new and desire to protect by Letters Patent is:

1. The combination with a car and door closing section therefor, of door holding means comprising a body, bolts extending

- through said body and the car door frame, and a movable abutment having slots therein receiving the bolts and formed at their ends with upturned latching notches for cooperation with said bolts, said abutment being slideable on said bolts from inoperative latched position within said body to operative latched position for holding one end of said section against outward dislodgment from grain sealing position, said bolts serving as guides for the abutment and also to secure the body to the car door frame.
2. The combination with a car and door closing section therefor, of door holding means comprising a body, bolts extending through said body and the car door frame, and a movable abutment formed with slots therein receiving said bolts, said abutment being slideable on said bolts from inoperative sheathed position within the body to operative projected position for holding one end of said section against outward dislodgment from grain sealing position, said bolts serving as guides for the abutment and also to secure said body to the car door frame.
3. The combination with a car and door closing section therefor, of door holding means including an abutment and an enclosing body therefor, said body comprising a side plate and flanges on said plate, bolts for clamping the body to the car door structure with the flanges of said body abutting against said structure, the abutment comprising a movable plate formed with slots therein receiving said bolts, said abutment being slideable on said bolts from inoperative sheathed position, between said side plate and car door structure, to operative projected position for holding one end of said section against outward dislodgment from grain sealing position, said bolts serving as guides for the abutment and also to secure said body to the car door structure.

In testimony whereof, I have signed my name to this specification.

JOHN A. SHISHUK.
